UNITED STATES PATENT OFFICE.

JAMES G. BRYANT, OF PORT HURON, MICHIGAN.

GRINDING-PLATE FOR MILLS.

1,114,339.

Specification of Letters Patent. Patented Oct. 20, 1914.

Application filed January 18, 1912. Serial No. 672,005.

To all whom it may concern:

Be it known that I, JAMES G. BRYANT, a citizen of the United States, residing at Port Huron, in the county of St. Clair and State of Michigan, have invented new and useful Improvements in Grinding-Plates for Mills, of which the following is a specification.

This invention relates to grinding mills, and has for its object to provide an efficient form of grinding plate adapted to accomplish the comminution of materials with a minimum liability of overheating, and which will insure performance of the grinding function uniformly throughout the area of the plate. That is to say, it is an object to avoid, in a mill employing oppositely rotating grinding disks, action upon the entire stock introduced therebetween immediately adjacent the eye or inner portions of the disks, whereby tendency to overheat is engendered as well as a waste of power incurred.

It is therefore a related object to provide such a construction of plates that certain quantities of grain or other material shall be conducted to outer portions of the disks or plates before being acted upon, while yet insuring accomplishment of the grinding operation upon other portions of material throughout the area of the plate. While accomplishing these ends it is desired at the same time to avoid excessive radial movement of disintegrated material under the action of centrifugal force, and the opposite extreme of lagging or circular movement, whereby material would tend to be held between the grinding plates longer than necessary.

In many prior devices having means to prevent grain from moving toward the periphery of the grinding elements too rapidly to be properly acted upon, the retarding elements have been of such form as to cause instant grinding or cutting of the material engaged thereby, whereby the main body of stock would be acted upon initially within a limited portion of the plates; and it is a most important object of this invention to effect retardation without involving grinding of the whole stock engaged by the retarding elements. The actual control of the radial speed of the stock is however not so much sought, as the accomplishment of initial treatment thereof over a wide area of the plate. It is not therefore desired to say that retardation is essential as the action

may be accomplished with comparative rapidity and yet thoroughly. The term retardation is employed as best calculated to convey the idea of the function sought, because the prior attempts toward the same end have usually involved the retardation of the stock from radial movement as exemplified in the patent to Davis, #827,059, July 24th, 1906, and also familiar in the dressing of millstones for a considerable period.

An important object is to provide an efficient distributing means for feeding material evenly to all portions of the space between the plates.

Other objects and advantages will be apparent from the following description and from the drawings, in which,

Figure 1 is a segmental view of one of my plates, Fig. 2 is a similar view of a modification, Fig. 3 is a section on the line 3—3 of Fig. 1, Fig. 4 is a similar view on the line 4—4 of Fig. 2, Fig. 5 is a fragmentary plan of a modified construction.

There is illustrated a disk 10 in Figs. 1 and 3, slightly reduced in thickness toward the center, whereby an enlarged throat 11 is provided adjacent the eye 12, when two plates are in operative position. The plate is intended to rotate in a given direction, indicated by the large arrow in Fig. 1 and the elements to be described may be considered as having each a front or forward side in the direction of rotation and a rear side opposite. The plate comprises a breast portion 13 having ribs 14 arranged with a view to the distribution of stock to the waist portion 15 immediately outward thereof. The ribs 14 are arranged in groups extending at a tangent to the axis of the disk, the ribs of each group being graduated in length, the shorter ones being located on the forward side of the group which is toward the direction of rotation of the disk. The inner ends of the ribs are arranged on a line diverging inwardly from the adjacent long rib at the rear side of the immediately adjacent group, whereby the bays 16 are formed, allowing ready access of stock to the spaces between all of the ribs and avoiding choking of the throat.

If desired, the breast and waist portion may be made in two separate parts, as shown in Fig. 2, and may be rotated at differentiated speeds, this being the preferable construction, the movements being in the directions indicated by the arrows.

The waist is provided with segmental groups 17 of short cutting and leading bars 18 in alined parallel series, bounded by the annular skirt bar 19. Certain series of 5 alined bars in each group, preferably those adjacent the rear side of the group, extend approximately in a radial direction, and those series at the forward sides of the groups—being parallel to the inner ones—10 become slightly tangential in direction and are made shorter in length. The groups are arranged in as narrow a form as possible to avoid too great a tangent in any of the bars. Each of the cutter bars is connected 15 at its outer end to the inner end of the next outer one laterally thereof in the direction of rotation, by connecting or grinding bars 20, which are thus inclined from their inner ends toward their outer ends in the direction 20 of movement of the plate. Zig-zag ribs are thus formed having between them a series of correspondingly shaped partly interrupted channels 21, the interruptions comprising the bars 20, now to be more particularly described. The forward or inner sides 25 of the bars 20 are gradually inclined to the base of the next adjacent bar across the respective channels 21, and the inner side of the skirt bar is similarly formed, as well as 30 those of the abutting grinding bars 20' connecting the outer ends of the adjacent bars 18 therewith. Alternate ones of the alined series of bars 18 in each group which could 35 extend uninterruptedly to the inner edge of the waist have the innermost bar 18 omitted, thus providing broad channel heads 21', and as the grinding bars 20 of the remaining inner cutter bars project but part way across this channel, this leaves an outer throat 24. 40 It should be noted that while the inclined sides of the grinding bars 20 extend across the channels 21 inwardly thereof, by reason of the corresponding direction of the channels themselves, a reduced clearance is 45 provided through which stock may pass outwardly should an excessive amount tend to accumulate before the grinding bars. The forward sides of the bars 18 are approximately vertical, although this angle may be 50 varied as found desirable, and at their rear sides they may be inclined outwardly toward their bases, or not, as found best. The rear sides of the grinding bars 20 may correspond in form to those of the bars 18. The 55 cutter bars, the grinding bars and the skirt bar all have broad flat upper surfaces or "lands" 25, upon which a certain amount of grinding action occurs, as distinguished from the cutting action occurring because of 60 the formation of the bar edges. The grinding action occurs particularly over the grinding bars, the sloping sides of which serve to raise particles into engagement between the lands of the opposed plates, no 65 matter how small the particles. It is desir-

able that a fillet be formed at the bases of those sides of all the bars which rise abruptly from the plate, whereby tendency of the channels to clog is lessened, as well as the liability of the bars to break off from 70 the plate reduced.

It should be noted that the tangent of the bars 14 of the breast is such as to deliver the stock radially from the throat to the cutting and grinding bars of the waist; and that in 75 the waist section the tangents of all the bars is less than that of the bars 14. These tangents may be varied, however, as found warranted. The bars 14 in conjunction with the superposed plate are intended principally to 80 roughly break the stock and then deliver it to the waist for finer comminution. The degree of reduction may be governed by the number of the grinding bars 20. By making the bars 18 short, the frequency of the grinding bars is increased, and by the use of a proper "runner" plate, pulverization may 85 be attained.

The plates are adapted to be formed with similar faces on each side, so that each side 90 may be used, and may be made in sections to be clamped or otherwise secured to carrying base members. These details are not illustrated, being mechanical expedients familiar 95 in the art.

The coöperating plate to be superposed over the one just described, may be similar, or otherwise formed. There is illustrated in Fig. 5 a slight modification of the described form, in which the connecting grinding bars between the cutter bars extend rearwardly and thereby avoid drawing stock inwardly when coacting with the grinding bars of an opposite plate constructed as 100 shown in the preceding figures.

In use, the stock, fed to the eye 12 in the customary way, is admitted in large quantities, because of the wide space between the plates, and the small number of ribs thereadjacent, and is rapidly admitted to the 110 grooves or channels between the ribs 14 of the breast. By these ribs the stock is roughly reduced and quickly delivered to the waist where it is further cut and ground by the bars 18 and 20. The channels between the ribs 14 allow the passage of the stock smoothly, without packing or heating, and the same is the case in the channels 21. cutting a part of the stock, lead a portion 115 In these channels, the bars 18, in addition to outwardly against the bars 20'. It will be apparent that all of the stock delivered from the breast ribs will not be engaged and lifted by the first grinding bar slopes encountered 120 if there is a very large quantity, and as there is a clear space forwardly thereof a portion of the roughly broken stock may reach the immediately adjacent outer parts of the channels 21, reaching the second set of 125 grinding bars. There are at least two chan- 130

nels thus to be reached by the material passing the first slope without being engaged. The inclination of the forward face of the grinding bars is such that even a single grain or portion of other material reaching it will tend to move upwardly thereover to be ground immediately; but when there is a large quantity of material tending to become packed in passing over the bar 20, there is a free lateral escape for the stock, which will quickly relieve the press and lead the stock without undue friction to the succeeding grinding elements where it may have its constituents treated without clogging, or the heating which might be attendant on too great a quantity of material being acted upon within a limited space. At the second set of slopes the same relief may be had, and some of the stock allowed to pass to the third slopes direct.

It is of special importance to consider the effect of forming the cutter bars and grinding bars with their slopes or lifting surfaces in a continuous rib. The lifting of the stock into engagement between disks is made most certain, by reason of the fact that the stock itself tends to become inert; and whether it does or not, it is impelled in the direction of rotation of the disk in the groove of which it lies by the rear side of the groove bearing thereagainst, or against intervening stock. As the stock moves outwardly along the channels and encounters in place of the abruptly extended side of the cutter bar the inclined surface of the grinding bar, it is most certain to rise thereon or be lifted thereby. Thus the liability of clogging, choking, or packing is much less than it would be if the raising of the stock were dependent entirely upon its inertia of motion radially or the pressure of following stock thereon. Both the factor of radial movement of the stock and that of lateral pressure of the sides of the groove thereagainst impelling the stock in a circular direction, are utilized to lift the material from the bottom of the groove in this device.

What is claimed is:

1. A grinding plate for mills having a stock groove including a plurality of portions adapted for movement of stock therein toward the periphery, and alternate connecting groove portions between those first mentioned and disposed obliquely thereto, the connecting portions having sloping rear sides adapted to engage and lift stock thereon, for the purpose described.
2. A grinding plate having a peripheral skirt bar and other inner bars formed thereon of tortuous shape and spaced to form continuous channels for the flow of stock from the center to the skirt, the inner bars including leading parts and baffle portions

extending obliquely thereto, the baffle portions having sloped sides to engage stock from an inner channel portion, for the purpose described.

3. A grinding plate having a skirt bar and inner bars, the majority of the bars each comprising a series of sections spaced laterally of each other in one direction and spaced from each other radially of the axis of rotation of the plate, and connecting portions having sloped sides disposed in the direction of rotation of the plate and channels extending continuously between all the bars from the skirt inwardly.

4. A grinding plate having bars each comprising a series of sections spaced laterally of each other in one direction and spaced from each other radially of the axis of rotation of the plate, and connecting bar portions having sloping sides in one direction and abrupt sides in the opposite direction forming cutting edges in combination with an opposed plate having similar bars, the connecting bar portions of which have oppositely arranged sloping sides and cutting edges.

5. A grinding plate having bars comprising in combination laterally and radially spaced cutter sections and diagonal parallel connecting bar portions connecting adjacent inner and outer ends of sections in laterally adjacent series, the sides of the connecting bar portions being sloped in the direction of rotation of the plate, said bars forming continuous channels for the flow of stock and partially interrupting lift portions for raising stock from the channels of which said bars form the sides.

6. A grinding plate comprising in combination a disk, bars thereon comprising series of parallel radially spaced cutter bar sections, certain of the series having their innermost sections omitted, and alternated series of parallel diagonal connecting bar portions connecting adjacent inner and outer ends of cutter bars in series spaced laterally in one direction, the sides of the connecting bar portions in the direction of rotation being sloped for engagement with stock flowing outwardly between inner cutter bar sections for lifting of a portion thereof, and adapted also to allow lateral escape of a portion of stock without grinding when tending to pack or clog the passages between the bars.

In testimony whereof I have hereunto set my hand in presence of two subscribing witnesses.
